BY

James Drew Stetson

ATTORNEY.

UNITED STATES PATENT OFFICE.

WILLIAM ARCHD. MURRAY, OF BOTHWELL, NEW ZEALAND.

WIRE-STRETCHER.

SPECIFICATION forming part of Letters Patent No. 650,983, dated June 5, 1900.

Application filed September 26, 1899. Serial No. 731,726. (No model.)

To all whom it may concern:

Be it known that I, WILLIAM ARCHIBALD MURRAY, a subject of the Queen of Great Britain and Ireland, residing at Bothwell, 5 Glen Murray, Auckland, in the Province of New Zealand, have invented a certain new and Improved Machine for Stretching Wire in Fences and Telegraph-Lines and Analogous Purposes, of which the following is a 10 specification.

My invention is an improved wire-stretcher; and it consists in the novel construction hereinafter set forth, whereby a device for the purpose stated is produced that will be of 15 light, durable, and efficient character and one that can be conveniently handled.

The accompanying drawings form a part of this specification and represent what I consider the best means of carrying out the invention.

Figure 1 is a general view showing the adjacent ends of two wires with the machine and chain in place. The succeeding figures show portions on a larger scale in two conditions. Fig. 2 is a side elevation showing the machine with the lever swung backward to obtain a fresh grip. Fig. 3 is a corresponding view showing the lever swung forward to the other extent of its motion, having correspondingly shortened the connection between the wires. Fig. 4 is a plan view corresponding to Fig. 3.

Similar letters of reference indicate corresponding parts in all the figures where they appear.

A is the operating-lever, which may be of hard wood faced and strengthened near the working end by plates of iron or steel.

B B are two base-bars set, mainly, at a sufficient distance apart to allow the lever to be fulcrumed on a pin C between them. The base-bars B B are bent together at one end, and the eyes B' on those ends are engaged through suitable provision with one of the 45 main wires, (marked P.) The other end of each of the base-bars is formed with a hook B², having a beveled outer face. (See Figs. 1 and 2.) A transverse stud B³ holds these ends of the base-bars a just-sufficient distance apart.

D D are two vibrating bars pivoted at one end to the lever A by means of a transverse

pin D'. The other ends of these bars are equipped with hooks D², corresponding to the hooks B², but facing downward. These bars 55 D are held a just-sufficient distance apart by a stud D³. The space between the two bars D D corresponds to that between the base-bars B B and in each is sufficient to receive alternate links of the chain and allow the 60 hooks to engage easily and reliably with the intermediate links. The lever A may be vibrated rapidly until the slack of the chain and wires is taken up; but in the last part of the tightening operation, the resistance being 65 considerable, the movements will be slower.

E F are the two series of links in the chain, each link E being short (shown as circular) and each link F being extended or oblong. Assuming the wire P to be stationary, the 70 chain E F is tied or otherwise strongly attached to the wire Q, which is to be drawn toward it, and the chain being held with its links E in the horizontal plane, and consequently with the links F in the vertical plane, the lever is vibrated and the hooks D² engaged at 75 each back movement over one of the horizontal links E. At each forward movement of the lever these hooks draw the chain along, so that toward the end of the movement a 80 new link E is presented and is easily engaged by the hooks B². Then another backward movement of the lever A relaxes the hold of the hooks D², and the chain being gently supported by the hand or otherwise these hooks 85 near the termination of the backward movement engage over a fresh link E, and the operation is repeated. When the chain has been sufficiently taken up and the wires P and Q have been brought together, their overlapping ends may be permanently joined in 90 any required manner.

Modifications may be made without departing from the principle or sacrificing the advantages of the invention. Other means than 95 the studs B³ and D³ may be used to hold each pair of hooks firmly at the proper distance apart. Besides the powerful contraction of a wire, as above described, the device can be used for a great variety of purposes, including the lifting or shifting of weights and commodities, tightening of bands in various situations, eminently around bales of goods, and in the pressing of cotton, hay, and the like.

t will obviously serve for tightening telegraph and trolley wires.

I claim as my invention—

In a wire-stretcher, the base-bar consisting of the braced parallel longitudinal sections bent inward toward each other and perforated at one end and presenting the double hooks at the other, a lever pivoted to the braces, a shorter hook pivoted to said lever, and a length of chain adapted for attachment to the

wire and comprising horizontal links E, substantially as set forth.

In testimony that I claim the invention above set forth I affix my signature in presence of two witnesses.

WM. ARCHD. MURRAY.
